UNITED STATES PATENT OFFICE

ALEXANDER D. MARRIOTT, OF DENVER, COLORADO, ASSIGNOR, BY MESNE ASSIGNMENTS, TO THE DORR COMPANY, INC., OF NEW YORK, N. Y., A CORPORATION OF DELAWARE

CLASSIFIER

Application filed October 17, 1930. Serial No. 439,267.

This invention relates to classifiers, and more particularly to that type of classifier intended to perform a classifying or sorting operation of particles of mixed sizes or different specific gravities, or both, by hydro-mechanical means. Such classifiers operate on the principle of settling of the heaviest and intermediate particles and overflow of the finer particles, the settled materials being removed from the settling tank by mechanical means.

Heretofore in classifiers of this type, two cooperating tanks have been employed, the upper one, known as the primary chamber or bowl, receiving the material and feeding the settling particles therefrom down through a central bottom opening into a secondary compartment. For such classifiers the feed from the bowl to the undercompartment has been by gravity, the material being again classified in the undercompartment so as to throw the lighter particles into suspension. By an upflow of the solution, the particles in suspension have been carried back into the bowl while the heavier materials settled in the secondary compartment have been removed therefrom by mechanical means, such as rakes.

Perhaps one of the greatest difficulties encountered in use of such classifiers, has been the interference between the large mass of settled material passing downwardly through the constricted opening at the same time particles in suspension are passing upwardly through the same opening. The present invention seeks to overcome this interference and resultant congestion.

Another drawback to classifiers as heretofore used is the loss of much material passing out with the overflow from the bowl as a result of the proximity of the inlet and overflow and critical nature of the particles which follow the overflow current rather than settle as they should. The present invention seeks to retain particles of such critical nature for reclassification and discharge.

In order to operate the classifiers as heretofore constructed, it has been necessary to introduce a considerable additional fluid, known as back-wash, into the secondary com-

partment so as to create a flow from the secondary compartment to the primary chamber or bowl. This back-wash obviously increases the dilution, and in many instances this type of classifier could not be used, as increased dilution is detrimental or objectionable from the standpoint of the resultant products. An inventive concept in the present case seeks to avoid or limit dilution and yet obtain the advantage of primary and secondary settling.

Construction of previously used classifiers has included elaborate means for feeding the material into the primary chamber, utilizing heavy and expensive feed wells, baffle rings and plates designed to overcome, to some extent at least, currents in the chamber created by the introduction of the material. The disclosure set forth herein eliminates those parts, and simplifies construction, use and operation of this type of classifiers.

Also, heretofore it has been difficult to obtain a classifier in which the material may be classified into several categories, such as coarse, intermediate and fine particles, so that one purpose of this invention is to devise a construction to obtain, generally as well as specifically, classification into two or more divisions in the one apparatus.

With the specific problems mentioned above in view and with the objects already stated in mind, with other objects and advantages as may more clearly appear in the following description, one embodiment of the invention is illustrated in the accompanying drawings in which like numerals of reference indicate similar parts throughout the several views, and in which:—

Figure 1 is a plan of a classifier constructed in accordance with the present invention;

Figure 2 is a sectional view taken substantially centrally across the bowl and longitudinally with respect to the secondary compartment, omitting the central partitions;

Figures 3 and 4 are detail sectional views of the floor of the pan and adjacent feed means on lines 3—3 and 4—4 respectively of Figure 1; and

Figure 5 is a sectional view on the line 5—5 of Figure 2 taken through the floor of the

pan and the bottom of the secondary compartment.

In the specific embodiment of the invention illustrated in said drawings, the basic construction shown provides two settling tanks identified as primary settling chamber or bowl or pan 1 and a secondary settling compartment 2 one end of which underlies the pan 1. The settling compartment is subdivided into longitudinal units 3, 3' by partitions 2'. The construction is such that parts of the settled material in the primary chamber can pass to either one or both units of the secondary compartment and the upflow from both units enters the pan as will be more fully explained hereinafter.

The pan preferably comprises a circular tank the bottom or deck of which is inclined so that a fluid in the pan will cover or submerge the lower portions of the bottom but will expose the upper portions of the bottom, this upper or non-submerged portion of the bottom constituting a drainage area. A rake 4 or other conveying element is provided in the pan for moving the settled material out of the lower part of the pan from submergence to the upper part thereof where the settled material is emerged from the liquid and discharge such material substantially peripherally of said pan. In the present showing this rake assumes an annular configuration substantially the diameter of the pan with a plurality of scoop-like blades 5 at the periphery thereof and adjacent the bottom or deck of the pan. These blades 5 are carried by inner and outer concentric rings 6, 7 respectively, the inner ring being connected by spokes 8 to a central hub 9 co-axial with the axis of the pan and rotated by suitable means such as a motor 10 with suitable driving and speed reduction connections as will be understood by those skilled in the art.

It is to be noted that the blades 5 are entirely submerged at the bottom of the pan below the normal level of the fluid therein so as to receive the settling materials, and as the blades are revolved and move through the fluid in the pan they gather up and remove therefrom a quantity of the settled material, carrying the same along an arcuate path over the deck of the pan out of the liquid into the exposed or drainage area. The material thus elevated and drained is then discharged.

In the present showing, discharge of the emerged material back to submergence may be effected to the secondary compartment, for which purpose an upper or non-submerged part of the deck of the pan overlying the secondary compartment is suitably apertured. Discharge of material from the pan to the secondary compartment is secured in this instance through two apertures 11, 12 in the upper part of the pan, one aperture overlying each unit of the compartment.

The construction shown is such that a portion

of the material will pass through one of the apertures and the remaining portion of material will drop through the other opening. By this means, the material is distributed between the two units of the secondary compartment. Preferably the apertures 11, 12 are at different radial distances from the center of rotation of the rake, but both within the path of movement of the blades, and as shown, the aperture 11 which is passed first by any given blade is next the outer periphery of the rake, whereas the second aperture 12 is nearer to the inner ring of the rake. Passage of a blade across the first or upper aperture results in the material nearest and outer end of the blade dropping through to the first unit of the secondary compartment, after which the blade continues its revolution and comes to the second or lower aperture where the remaining material carried forward by the inner end of the blade falls through to the second unit of the secondary compartment.

If desired, either or both of the apertures 11, 12 may be closed so as not to permit passage of the material into either or both of the compartment units. For illustrative purposes, these apertures are shown as having swinging gates 13, 14 respectively pivoted flatwise beneath the bottom or deck of the pan. These gates may be opened or closed at will to obtain classification as desired. In event both gates 13 and 14 are closed, discharge of the material may be obtained through an exit aperture 15 reached by any given blade after passing both of the closed apertures. This exit aperture 15 is preferably of a size such that all of the material from the blades will drop through the same. A closure, such as gate 16, may be provided for this exit aperture also, said gate being shown pivoted flatwise against the underside of the bottom or deck of the pan. It is to be noted that this exit opening is at a part of the pan not overlying the secondary compartment so that the discharged material falling therethrough will not enter the compartment but may be conveyed off or otherwise handled as found most expedient.

The secondary compartment, as above indicated, preferably comprises a pair of similar units, and these units are shown side by side in parallel relation, both sloping from a position under the pan to a position removed a considerable distance laterally from the pan and well above the normal fluid level therein. This part of the structure is in most part old in the art, reference being had to Patent 1,292,237 of January 21, 1919 issued to Blomfield for a detailed description thereof. In general, each unit is in the form of an inclined trough in which a mechanically operated reciprocating rake 16 actuates settled material upwardly with a step by step motion. The rake is carried by two hangers

17, 18, one, as 17, near the discharge end and the other, 18, toward the lower end, both hangers being supported by interconnected bell cranks 19, 20 respectively, the upper one 19 of which has a rocker lever 21 depending therefrom for actuation by a cam 22 driven through suitable reduction gears by a motor 23. This motor, with attendant reduction gears and shafts, may obviously be common to the several units as indicated in the drawings. The structure as above outlined obtains an offsetting movement of the entire rake toward and away from the bottom of the trough. Reciprocation of the rake is obtained by a crank-operated pitman 24, this reciprocal movement, combined with the offsetting movement, resulting in an orbital movement of the rake by which the materials settling on the bottom of the trough will be intermittently dragged up the incline with a step by step motion. The material is thus stirred up and the fine particles thrown into suspension in the fluid, but the heavier particles remain on the inclined floor of the unit 25 and will be repeatedly pushed up the incline until finally discharged at the upper end thereof.

Heretofore, in classifiers of this general type, the material to be treated has been introduced into the primary chamber and the large particles have been raked to a central aperture where they have dropped into the secondary compartment; the fine particles using that same aperture but in a reverse direction to return from the secondary compartment to the primary chamber. Such construction has proven to require an unnecessary expenditure of power, time and effort, in that all of the heavy particles have to be raked in both tanks. By the present invention, this action is greatly simplified. Means are provided herein for introducing the material to be treated into the secondary compartment first so as to subject the material immediately to the stirring action of the reciprocating rakes to throw into suspension both the fine particles and some intermediate or critical particles. Thus, the heaviest particles, not entering the primary chamber 50 at all, reduce interference and congestion heretofore existing in that chamber.

Passage of the fine particles and critical particles in suspension is permitted to the primary chamber through upflow openings 55 25, 25 provided in a submerged portion of the deck of said primary chamber. As shown, the said openings are over the lower ends of the units, one for each unit, and between the path of the blades in the pan and the center 60 of the pan. By this arrangement the rising solution from said upflow openings will have no disturbing effect on particles settled into the blade area, nor will that settled material interfere with the upflow from the secondary compartment. It will also be observed that

the entry of the solution and particles to the pan is by a different opening than that through which the material is discharged therefrom. This feature is important, as it reduces interference and eliminates congestion. 70

The effluent or outflow of the fluid with fine particles in suspension is obtained by a launder 26 preferably overlying the area of submerged revolution of the rake blades. This arrangement directs such current as exists in the fluid toward the area of the blades so that the settling particles will encounter the blades and be discharged thereby. However, it is desirable to minimize the current in the fluid as much as possible, particularly where the fluid passes over the weir 27 to the launder, since a large volume or a swift current passing over a weir will carry correspondingly larger particles, and it is desired to permit escape or fine particles only. As shown, the discharge launder 26 is a semicircular trough spaced inwardly from the periphery of the pan for the deeper portion thereof. The two upper arcuate edges of this trough or launder are in a common horizontal plane at substantially the normal fluid level in the pan and constitute weir 27 above mentioned. Since both edges of the launder are free and within the pan, the fluid in the pan will have access 90 for discharge purposes to both sides of the trough thus reducing the discharge velocity over the said sides or weirs to one half of the velocity which it would have were only one side of the trough accessible to the fluid as a weir. The bottom of the trough preferably slopes downwardly to a middle part of its length and there discharges through a sluiceway 28 through the side of the pan. This sluiceway 28 is obviously a passage laterally 105 from the trough but closed with respect to the fluid content of the pan so as to prevent escape of the fluid except by way of the weir, launder and thence into the sluiceway.

From the above description, it will be understood that, contrary to previous practice, the material to be treated is introduced initially into the secondary compartment or classification zone rather than into the primary chamber. According to the present disclosure, this initial introduction is above the lower end of the secondary compartment, between the upper apertures 11, 12 and lower openings 25. By this arrangement, the lower ends of the rakes and rake compartment are not likely to become congested, and interference by the introduced material with upflow through the lower openings 25 of the pan is avoided. 110

A pipe or conduit 29 is shown at one side 120 of the secondary compartment illustrative of means for conveying the material to be treated to the desired position for introduction to the compartment. This conduit is shown entering beneath the pan between the 125

pan and compartment in a direction longitudinally of the compartment. At a proper position under the pan, the conduit is directed laterally so as to be positioned over the compartment, this lateral portion being shown as a double conduit, one portion 30 of which extends to a position over the middle of the first unit where it has a discharge opening 31, and the other portion 32 of the conduit extends on over to the second unit with a discharge opening 33 over the middle of that unit. These two conduit portions 30 and 32 will therefore split the feed or supply of material and discharge part thereof into each unit for classifying. Means may be provided in connection with the supply conduit to permit feed to both units or to only one unit. One such means is exemplified by a valve or gate 34 in the double portion of the conduit which valve may lie across either portion of the conduit or may stand in a neutral position. Obviously when the valve stands across either portion of the conduit, flow through that portion is stopped but flow through the other portion continues. When the valve is in neutral position, flow of material is permitted in both portions of the conduit to both units.

A second feed conduit 29' is provided at the outer side of the unit 3' of the secondary compartment for feeding the unit 3' from an outside source different from that which supplies the feed conduit 29. This is especially useful in closed circuit, primary and secondary grinding where it is desirable to operate the unit 3' in closed circuit with a secondary mill. Where the materials handled in the different units 3 and 3' are different, as in primary and secondary grinding it is preferable to arrange the different units with different slopes. For example, a slope of $3\frac{1}{2}$ inches per foot for unit 3 and a slope of 2 inches per foot for unit 3'.

Since the material is introduced into the secondary compartment, and since only a part of that material settles so as to be raked out, there will be an excess of material for obtaining an upflow from the secondary compartment to the primary chamber. The classifier is therefore capable of operation without introduction of any backwash, which is frequently an important consideration, especially since the velocity over the discharge weir is a function of the amount to be discharged and the loss of desired or critical particles is a function of that velocity. However, for obtaining dilution or backwash when needed, a spray pipe 35 is provided across the secondary compartment at a position intermediate the upper or discharge end thereof and the pan. Any suitable means (not shown) may be employed to regulate the supply of backwash supplied by this pipe as will be understood.

To separate the discharge of intermediates

flowing from the primary compartment through openings 11 and 12, from the openings 25, a baffle 36 is arranged to extend down into the secondary compartment between the upper group of openings 11 and 12 and the lower group of openings 25. This provides a clear zone of back-wash water through which the material of intermediate size from the primary compartment is dropped into the secondary compartment.

Where desirable, the openings 25 at the lower portion of the primary compartment may be omitted and the flow from the secondary compartment to the primary compartment thereby caused to take place through one or both of the openings 11 and 12.

This improved classifier is adapted for use in several ways. In any event the material to be treated is introduced into the secondary compartment for initial classification. With the use of two units for the secondary compartment, the material may be introduced into only one unit or into both units. Supposing the material is introduced into both units, with the conduit valve in neutral, it will be seen that the coarse settling will then be discharged over the top of both units and the particles thrown into suspension will pass up through both openings 25, 25 in the lower part of the bowl. The pan will then classify between fine and intermediate particles. Now if both gates to the upper apertures 11, 12 in the pan to the compartment are open, the intermediate particles then return to the two units and will discharge in most part with the larger particles. Thus, the classifier operates to separate into two classifications. If, on the other hand, initial supply of material is to only one unit and discharge from the pan is to the other unit only, classification three ways will be effected, that is, the first unit will discharge the coarse particles, intermediate and fine will pass up to the pan where the fine passes out with the overflow and the intermediate is discharged to the second unit. In the second unit, the product is reclassified, returning any fine particles to the pan, and thus a very clean intermediate product is obtained. Should the character of the intermediate product not be needed so perfect, it may be caused to discharge from the exit aperture 15 by opening the gate thereto and closing the gate to the second unit.

For closed circuit, primary and secondary grinding, the gate 34 is adjusted to divert into the unit 3 of the secondary compartment the feed pulp from a primary grinding mill; the primary compartment openings 11 and 15 closed; and the feed conduit 29' connected to receive the discharge from a secondary grinding mill, while suitable provision is made for returning the discharge from the upper end of secondary units 3 and 3' to the

primary and secondary grinding mills respectively. Thus under such operation, discharge from the primary mill will be fed directly into unit 3 of the secondary compartment where a relatively coarse separation is made, the coarser material being raked to the upper end and returned to the primary mill while the finer material flows to the primary compartment. The material of intermediate size settled out in the primary compartment is discharged therefrom through opening 12 into unit 3' of the secondary compartment, thence raked to the upper end and conveyed to the secondary mill from which after further grinding it is fed directly into unit 3' of the secondary compartment, from which the finer material flows through opening 25 into the primary compartment, the finished product overflowing the primary compartment.

Obviously other detail changes and modifications may be made in the construction and use of the improved classifier constituting the present invention, and it is to be clearly understood that the invention is not limited to the exact structure or operation shown or described, except as set forth in the following claims when construed in the light of the prior art.

Having thus described the invention, I claim:—

1. Apparatus of the class described having a classification compartment, a sedimentation compartment forming a top for the lower end of said classification compartment and inclined in a single plane with respect to the liquid level therein, an inlet from the classification compartment to the sedimentation compartment located in the lower end of the classification compartment, an outlet from the sedimentation compartment to the classification compartment, and rotary means for conveying sedimented material from the sedimentation compartment to said outlet.

2. Apparatus according to claim 1 in which the conveying means convey the sedimented material upwardly against gravity.

3. Apparatus of the class described having a plurality of separate classifying compartments, a single sedimentation compartment superposed upon said classifying compartment and inclined in a single plane with respect to the liquid level therein, an inlet to said sedimentation compartment in the lower end thereof from said classifying compartments, an outlet in the upper part of said sedimentation compartment to each of said classifying compartments, and means for controlling exit of material from said sedimentation compartment through said outlets.

4. Apparatus of the class described having a raking classifier, a material feed therefor, a sedimentation compartment superposed on one end of said classifier provided with an inclined partially submerged deck, means for

flowing material from said classifier upwardly into said sedimentation compartment, a discharge above liquid level in said compartment into said classifier, mechanism for propelling submerged solids upwardly on said deck to a point of emergence from liquid over said deck whereby the solids are cleansed, and means for returning said cleansed solids to resurgence in said classifier through said discharge.

5. Apparatus of the class described having a raking classifier provided with a clean sand discharge, a material feed therefor, a sedimentation compartment communicating with said classifier having a partially submerged deck, an overflow therefrom for fine material, means for cleansing sedimented material in said compartment by conveying the material up said inclined deck to non-submergence, and means for returning the cleansed material to re-submergence in said classifier.

6. Apparatus of the class described having a raking classifier, a sedimentation compartment communicating therewith through the medium of an inlet from classifier to compartment and a discharge from compartment to classifier, a launder for feeding material initially to said classifier located between said inlet and discharge and a baffle to keep separated the discharge from the sedimentation compartment and the feed to the classifier.

7. Apparatus of the class described comprising a raking classifier, a deck superposed on one end thereof, a submerged inlet from classifier to deck, a non-submerged outlet from deck to classifier and means for conveying material on said deck from said submerged inlet to said non-submerged outlet.

8. Apparatus of the class described having a raking classifier, a pan superposed on one end thereof, a submerged inlet from said classifier to said pan, a non-submerged outlet from said pan to said classifier, and means for conveying material in said pan from said inlet to said outlet comprising scoops arranged around the periphery of said pan, radial arms providing support for said scoops, and a rotatable shaft for rotating said arms.

9. Apparatus of the class described comprising a raking classifier, a deck superposed on one end thereof, a submerged inlet from classifier to deck, a non-submerged outlet from deck to classifier, means for conveying material on said deck from submergence to non-submergence, and means for returning said non-submerged material to re-submergence in said classifier.

In testimony whereof I affix my signature.
ALEXANDER D. MARRIOTT.
